(57) **CLAIM**

The ornamental design for a joystick control actuator, as shown and described.

DESCRIPTION

FIG. 1 is a perspective view of a joystick control actuator showing our new design;

FIG. 2 is a front elevational view thereof;

FIG. 3 is a right side elevational view, the opposite left side elevational view being a mirror image;

FIG. 4 is a rear elevational view thereof;

FIG. 5 is a top plan view thereof;

FIG. 6 is a bottom plan view thereof;

FIG. 7 is a rear elevational view of a second embodiment showing our new design;

FIG. 8 is a right side elevational view of our second embodiment, the opposite left side elevational view being a mirror image; and,

FIG. 9 is a bottom plan view of our second embodiment of FIGS. 7 and 8.
